(57) **CLAIM**

The ornamental design for a data cable, as shown and described.

DESCRIPTION

FIG. 1 is a front, left and top perspective view of a data cable, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof shown on an enlarged scale for clarity of disclosure; and,

FIG. 7 is a bottom plan view thereof shown on an enlarged scale for clarity of disclosure.

The broken lines shown in the drawings illustrate portions of the data cable that form no part of the claimed design.

1 Claim, 7 Drawing Sheets(56)
